CLAIM

I claim the ornamental design for a light bulb-heated, three-legged animal feeder/waterer with removable container, as shown and described.

DESCRIPTION

FIG. 1 is an exploded perspective view of a light bulb-heated, three-legged animal feeder/waterer with removable container showing my new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.

The chord element shown in FIGS. 1, 3, 4, 5 and 6 on the base portion of the claimed design is understood to be of indeterminate length.

It is understood that the heating element shown inside the base portion of FIG. 1 is a conventional light bulb.
